CONTAINER

Wilfred R. Fox, Flint, Mich.

Application March 2, 1940, Serial No. 321,924

3 Claims. (Cl. 229—51)

This invention relates to an improved container especially intended for the packaging of merchandise.

Since the development of various plastics suited to the packaging of goods, the use of such material has spread rapidly as the value of a transparent container in different new fields has been quickly recognized. An object of the present invention, therefore, is to provide a novel container of this kind for cigarettes.

A further object of the invention is to provide a container wherein the tips of the cigarettes will be visible at one end of the package at least, and wherein the container may be conveniently loaded and sealed.

Still another object of the invention is to provide a container embodying a means whereby the container may be easily and quickly opened to permit ready access to the cigarettes.

A further object of the invention is to provide a container wherein the operation of opening the container will cause a flap to be defined, which flap will normally serve to prevent accidental loss of cigarettes from the package.

And the invention seeks, as a still further object, to provide a container which will be neat and attractive in appearance and which may be produced economically.

Other and incidental objects of the invention will appear during the course of the following description of the invention, and in the drawing:

Figure 1 is a plan view of the blank from which the body of the container is formed.

Figure 2 is a perspective view of the container-body as well as the cap employed, the parts being detached.

Figure 3 is a perspective view showing the manner in which the container is loaded.

Figure 4 is a perspective view showing the container loaded and sealed.

Figure 5 is a perspective view showing the manner in which the container is opened.

Figure 6 is a perspective view showing the manner in which cigarettes may be extracted from the container.

Figure 7 is an enlarged detail perspective view of the cap.

In the drawing, I have shown my invention embodied in a container for cigarettes and will so describe the device. However, as will be appreciated as the description proceeds, the invention may be embodied in containers for various other commodities such, for instance, as candy, chewing gum or other articles of mer-

chandise, and I do not, therefore, wish to be limited in this regard.

In Figure 1, I have shown an oblong blank 10 at one end of which is a flap 11 while at the lower margin of the blank appropriate slits define flaps 12 and 13. At the upper margin of the blank is a more or less narrow lip 14 and formed at the base of said lip is a shoulder 15. Preferably, the blank 10 is formed of suitable plastic material possessing the necessary resiliency and capable of being sealed either by heat or an appropriate cement. Several so-called plastics are available and choice may depend upon which is best suited to the purpose. For certain adaptations of the invention, however, foil, paper or other suitable material may be found expedient and, as will be appreciated, by properly printing a sheet of the material, several of the blanks 10 may be fashioned therefrom simultaneously.

As seen in Figure 2 of the drawing, the blank 10 is folded to produce a rectangular container-body 16, the ends of the blank being connected by the flap 11 secured either by the application of heat or by cement, as found expedient. Thus, as will be noted, the lip 14 is disposed to extend about the upper end of the container-body while the flaps 12 and 13 provide side and edge flaps at the lower end of the body.

In conjunction with the body 16, I provide a rectangular cap 17, shown in detail in Figure 7 of the drawing. This cap is provided with a side wall 18 and a top wall 19 and is molded as a complete unit preferably from plastic material of the character previously noted although, however, other materials may be employed if possessing similar qualifications. In any event, it is intended that the cap shall be a moulded unit. Furthermore, the cap is preferably transparent, which may or may not be true of the body 16, depending upon choice. By forming the cap 17 of the same material as the body 16, however, it is conceivable that, if so desired, the cap and body may be moulded as an integral structure, thus eliminating the blank 10. Similarly, for certain adaptations of the invention, it may prove advantageous to mold the cap and body separately.

Formed in the side wall 18 of the cap at one end thereof are guide grooves 20 defining an intervening tear band 21 which terminates at one end in a tab 22 free at its outer extremity. Thus, the tab may be readily grasped for tearing the band 21 from the cap and, as will be noted, the grooves 20 are joined at the base of the tab and

at the end of the band opposite the tab by like grooves 23 so that the tear band may be easily torn free of the cap. In some instances, it may prove advantageous to form the band 21 somewhat thicker than the walls 18 and 19 of the cap in order to provide additional strength in the band itself so that the band may be certain to tear free without breaking and, of course, as the cap is a moulded unit, the increase in the thickness of the band may be added either at the inside or the outside of the cap, as found desirable. Formed on the top wall 19 of the cap, medially thereof, is a longitudinally extending stiffening rib 24 which extends across the plane of the grooves 23.

It is now to be noted that the cap 17 is shaped to snugly fit over the lip 14 at the upper end of the body 16 resting against the shoulder 15 at the base of said lip. Heat may be applied for connecting and sealing the parts or an appropriate cement may be used. Thus, the cap will effectively close the container at its upper end. As suggested in Figure 3 of the drawing, the container is then filled or loaded with cigarettes, when the flaps 12 and 13 are folded down and sealed, either by the application of heat or an appropriate cement, to produce the finished package shown in Figure 4. As will be observed, the upper ends of the cigarettes project into the cap 17 and are readily visible and, if so desired, the construction at the upper end of the container may be duplicated at the lower end thereof, in lieu of the flaps 12 and 13, so that the container would be provided at both ends with caps through which the ends of the cigarettes could be seen.

To open the container, the package may be held as suggested in Figure 5 of the drawing, when the tab 22 is grasped and the band 21 torn free. As will be perceived, this operation will also serve to free the adjacent end portion of the top wall 19 of the cap 17 to provide a flap 25 stiffened by the rib 24 to normally lie against the ends of the cigarettes therebeneath. Accidental loss of cigarettes from the package will thus be prevented. However, as suggested in Figure 6, the flap 25 may be readily flexed back when one or more cigarettes may be conveniently grasped and withdrawn from the package. As will be observed, the removal of the tear band 21 serves to appreciably shorten the side wall 18 of the cap beneath the flap so that the upper

ends of the adjacent cigarettes are exposed and may be readily grasped between the thumb and finger. Mutilation of the cigarettes, incident to the removal thereof, will thus be avoided.

5 Having thus described my invention, I claim:

1. A container including a pliable plastic container-body embodying a single blank fashioned to provide a lip at one end of the body and flaps at the opposite end of the body capable of being folded for closing the body after being filled, and a plastic cap moulded as a preformed imperforate unit to mate with the body and shaped to fit over said lip united therewith by the application of heat, said cap including a side wall

10 having spaced guide grooves indented therein to define an intervening tear band terminating at one end in a tab free to be grasped for manually tearing out said band.

15 2. A cigarette container including a pliable

20 container-body embodying a blank fashioned to provide a lip at one end of the body and flaps at the opposite end of the body capable of being folded for closing the body after being filled with cigarettes, and a plastic cap moulded as a pre-

25 formed imperforate unit to mate with the body and shaped to fit over the outside of said lip and secured thereto, the body being shorter than the cigarettes whereby corresponding ends thereof project into the cap and the cap being trans-

30 parent for displaying said ends of the cigarettes to view.

3. A cigarette container including a container-body, and a plastic cap moulded as a preformed imperforate unit to mate with the body and

35 shaped to fit over one end thereof hermetically sealed thereto, said cap being provided with a top wall and a side wall which latter is provided about one end portion of the top wall with substantially parallel moulded guide grooves therein connected at their ends by moulded transverse

40 guide grooves to define an intervening tear band terminating at one end in a free moulded tab joined at its base with the band at one of said transverse grooves, whereby the tab may be pulled

45 for tearing the band free to be severed at its

ends from said side wall at said transverse

grooves and along its longitudinal edges at said

parallel grooves and release said end portion of

50 said top wall to provide a retaining flap over-

lying the ends of cigarettes therebeneath.
